UNITED STATES PATENT OFFICE.

IRVING B. SMITH, OF PHILADELPHIA, PENNSYLVANIA, ASSIGNOR TO ELECTRELLÉ COMPANY, OF PHILADELPHIA, PENNSYLVANIA, A CORPORATION OF PENNSYLVANIA.

AUTOMATIC MUSICAL-INSTRUMENT PLAYER.

No. 923,380.

Specification of Letters Patent.

Patented June 1, 1909.

Application filed November 21, 1907. Serial No. 403,148.

To all whom it may concern:

Be it known that I, IRVING B. SMITH, a citizen of the United States, residing at Philadelphia, in the county of Philadelphia and State of Pennsylvania, have invented new and useful Improvements in Automatic Musical-Instrument Players, of which the following is a specification.

This invention relates to certain new and useful improvements in automatic musical instrument players of the general type illustrated in my pending application, Serial No. 276,189, filed August 29, 1905, wherein the hammer-actuating mechanism is located in the upper part of the instrument casing, as for instance, in the upper part of the casing of an upright piano; and which actuating mechanism in the present embodiment of the invention comprises in part a rotary shaft or roll, and a plurality of friction shoes coöperatively associated therewith and adapted to be actuated thereby, the said shoes each having a flexible tape or cord connection with a part of each individual hammer action and serving to impel the piano hammers against their strings.

It has been found in practice when adjusting the flexible tapes or cords on the player action, that in some makes of pianos it is difficult to set them exactly right for both loud and soft tones, it being evident that if there is too much slack in the tapes or cords the hammer actions will not be moved sufficiently and properly to cause the hammers to strike the strings. To understand this more clearly consider the operation of the piano when played either by the automatic player mechanism or by hand. In striking a key the hammer-jack impels the action until the escapement releases the jack. The hammer continues to travel forward, striking the string, rebounds and the back-stop impinges the back-check thereby bringing the hammer to rest before it returns to the hammer rail. If it struck the hammer rail only and not the back-check, the hammer would rebound. This on a loud or "forte" tone would do no particular harm, except to affect the touch in a manner to be somewhat annoying in hand playing. In soft or "pianissimo" tones, however, the hammer rest-rail, and consequently the hammers, are moved very close to the strings and then if the back-stop does not properly engage with the back-check it may not damp the hammer movement and

the hammers may, after striking the hammer rail, rebound so far as to strike the strings again giving rise to very undesirable and unpleasant notes. Now in practice it is found that if the flexible tapes or cords are made just the proper length when playing loud tones (that is, with the hammer rail out of normal position, namely; that position which causes the hammers to lie farthest from the strings) the tapes will often be found too long when playing soft tones (i. e., when the hammer rail is advanced). That is, the tapes or cords have so much slack that they will not lift the wippen high enough to cause the back-check to properly hold the back-stop when the hammers return from striking the strings.

The present invention, therefore, relates primarily to mechanism for automatically taking up enough of the slack in the flexible tapes or cords to cause them to properly raise the wippens, and cause satisfactory engagement of the back-checks and back-stops, and insure proper operation of the piano hammers.

In the present showing which is merely for illustrative purposes the tape-adjusting mechanism is shown coöperatively associated with a known form of expression mechanism, but it will be obvious that the same may be employed in connection with other forms of expression mechanism.

In order to enable others skilled in the art to understand, make and use the improvements, these will now be described in detail, reference being had for this purpose to the accompanying drawings, wherein—

Figure 1 is a vertical sectional view of the upper portion of an upright piano, having one form of player mechanism, and automatic tape slack-adjusting mechanism coöperatively associated therewith; Fig. 2 is an enlarged detail end elevation of the slack adjusting mechanism; and Fig. 3 is a broken front elevation of the slack adjusting mechanism coöperatively associated with the expression mechanism. Fig. 4, is a detail sectional view showing the construction and manner of attaching the arms 26, to its rock shaft and the lever 23, to its arm.

Referring to the drawing the reference letter A designates the casing of a musical instrument, in the present instance shown as an upright piano; b one of the piano strings; c a hammer head; d a back-stop; e, a back check; f a wippen; g action extension, and h

a finger key, all of which parts may be of any preferred construction.

The automatic playing mechanism is located in the upper part of the instrument casting, in front of the strings, and preferably above the hammer heads. This mechanism, in the present showing, and which is merely illustrative of one embodiment of the invention, comprises a rapidly rotating shaft or roll 5, above which is located a plurality of friction shoes 6, each pivoted to the armature 7 of an electro-magnet 8, there being a friction shoe and coöperating electro-magnet for each individual hammer action, or as many as it is desired to operate automatically. The friction shoes are normally held out of contact with the shaft or roll 5, and therefore normally inactive, but are brought into contact with the said shaft or roll and thus rendered active, whenever the electro-magnets 8 are energized, this being accomplished by completing the electrical circuits in which the magnets are included, through medium of a suitable record, such as a perforated music sheet (not shown). A flexible tape or cord connection 9 is provided between each friction shoe 6, and the wippen *f* of the appropriate hammer action, the arrangement of parts being such that whenever a friction shoe is brought into contact with the rapidly rotating shaft or roll, said shoe will be kicked forward, giving a sudden jerk or pull upon its tape or cord which will result in an actuation of the hammer action and cause the hammer to strike the string. This mechanism is shown and described in detail in my aforesaid pending application and need not be gone into here with greater particularity. Also embodied in the instrument and associated with the piano hammers is an expression mechanism comprising a flexible bar which acts as a hammer-rest, means being provided for moving the said bar, and with it the hammers, toward and from the piano strings to effect pianissimo, forte, fortissimo, and crescendo expressions.

For the purposes of illustration I have selected the general type of expression mechanism shown and described in my aforesaid pending application, and in my prior patent No. 777,226, dated December 13, 1904, which comprises a flexible hammer rest rail made up of two sections 12, 12, pivoted together at their adjacent ends as at 13. This rail serves as a rest for the piano hammers and the sections thereof together with the hammers are designed to be moved, either collectively or independently, in order to shift the position of rest of a series of hammers whereby the length of stroke of the successive hammers of the series will vary from end to end of the series, with the result that a wide range of artistic musical expressions may be obtained, all as set forth with great particularity in my aforesaid application and patent.

The mechanism for operating the hammer-rest-rail sections comprises three separate rock-shafts 14, 15, 16, to each of which is attached an arm 17, which arms support and carry the hammer-rest-rail by having connections therewith respectively, at its opposite ends and intermediate its ends. The rock-shafts may be operated so as to actuate the rest-rail and piano hammers by any suitable means, preferably under the control of the performer when seated at the instrument, the means herein shown consisting of finger keys 18, pivoted beneath the piano key-board, each said finger key 18 having a connection 19 with an arm 20, fixed to its appropriate rock-shaft.

As heretofore mentioned, it has been found in practice when adjusting the flexible tapes or cords 9, that connect the friction shoes 6 and wippen *f*, in some makes of pianos, it is difficult to set them exactly right for both loud and soft tones, so there will be no slack. It is the prime purpose of this invention to provide means for automatically taking up the slack in the tapes, said means being co-operatively associated and operable simultaneously with the expression mechanism.

In the present embodiment of the invention a flexible tape-adjusting-rail is employed, over which the flexible tapes or cords 9 pass, and through the movement of which the slack in the tapes may be taken up, said rail being arranged transversely of the tapes or cords and preferably located at a point below the plane of the friction shoes, as clearly shown in Fig. 2 of the drawing. This flexible tape-adjusting-rail is made up of a plurality of alined sections 21, which may or may not be jointed at their adjacent ends, depending upon the type of expression mechanism with which it is associated. In the present instance the rail is shown as jointed at 22, and is supported by three levers 23, each pivoted intermediate its ends, as at 24, to suitable brackets 25, one of said levers being connected at its lower end to each end of the tape-adjusting-rail sections 21, and the other or middle one of the three having a swiveled connection with the adjacent jointed ends of said sections, as more clearly shown in Fig. 2. The three levers 23 each have separate operable connections at their upper ends with the three rock-shafts 14, 15, 16, of the expression mechanism so as to be operated in such manner as to move the tape-adjusting-rail and take up the slack in the tapes or cords as it occurs during the operation of the expression mechanism. One manner of operatively connecting the levers 23 to the appropriate rock-shafts is by means of an arm 26, secured by a set-screw 27 to each rock-shaft, so as to partake of the movements thereof, each arm 26 being provided with a slot or bifurcation 28, which takes over the shank of a screw 29, passing

through an elongated slot 30 formed in each lever 23, the said screws 29 being held in position by means of lock nuts 31, as more clearly shown in Fig. 4. The screw 29, serves 5 as a pivot or pivotal joint between the arms 23, and 26. By this arrangement it will be seen that the position of the tape-adjusting rail sections will be shifted whenever the hammer rest-rail sections are shifted and in a 10 corresponding manner, but in a reverse or opposite direction. For instance, assuming that one or both sections of the hammer-rest-rail and hammers resting thereagainst is moved from normal position (which is close 15 up to the piano strings) to a position farther removed from the strings, then the tape-adjusting rail, through the jointed connections with the rock-shafts, as heretofore described, will be simultaneously and proportionately 20 moved to take up and compensate for any slack that may occur in the flexible tape or cord connections 9, between the friction shoes 6 and wippens 7 of the hammer actions. The amount of movement imparted to the 25 tape-adjusting rail may be adjusted or varied as desired, to suit the varying conditions as found in different makes of pianos, by simply adjusting the position of the screws 29 in the elongated slots 30 of the levers 23, which adjustment will, as is obvious, shift the point of leverage and consequently vary the throw of the levers.

The slack-adjusting mechanism herein shown and described is illustrated by way of example in connection with the shoe and roller construction of actuating means disclosed in my prior patents and applications, but the invention is by no means limited to this application, as it will be obvious that the 40 same may be employed in connection with other forms of actuating means.

Having thus described my invention, what I claim as new and desire to secure by Letters Patent is:—

45 1. In combination, a sound-producing device, an actuator therefor, a flexible connection between the said device and actuator, and means for maintaining said flexible connection operatively taut.

50 2. In combination, a sound producing device, an actuator therefor, a flexible connection between said device and actuator, and means for taking up the slack in said flexible connection.

55 3. In combination, a sound-producing device, an actuator therefor, a flexible connection between said device and actuator, and means coöperatively associated with said flexible connection for taking up the slack 60 therein.

65 4. In combination, a sound-producing device, an actuator therefor, a flexible connection between said device and actuator, and means under the control of the performer for taking up the slack therein.

5. In combination, a sound-producing device, an actuator therefor, a flexible connection between said device and actuator, and manually operable means coöperatively associated with said flexible connection for taking up the slack therein. 70

6. In music playing mechanism, the combination with the sound-producing devices, of actuators therefor, flexible connections between said sound-producing devices and actuators, and means coöperatively associated with the said flexible connections for taking up the slack therein. 75

7. In combination, a piano hammer action, an actuator therefor, a flexible connection between a part of said action and said actuator, and means for taking up the slack in the 80 said flexible connection.

8. In combination, a piano hammer action, an actuator therefor, a flexible tape connecting a part of said hammer action and said actuator, and manually operable means for taking up the slack in said tape. 85

9. In automatic music playing mechanism the combination with the sound-producing devices, of a plurality of actuators therefor, flexible connections between said devices and actuators, expression mechanism for varying the expression of the sound-producing devices, and means coöperatively associated with said expression mechanism for taking up the slack in the said flexible connections between the sound-producing devices and actuators. 90

10. In combination, a plurality of piano hammer actions, actuators therefor, flexible connections between said actuators and hammer actions, expression mechanism coöperatively associated with the hammers for moving them toward and from the piano strings, and means for taking up the slack in said flexible connections. 105

11. In combination with a plurality of piano hammer-actions, actuators therefor, flexible connections between said actuators and hammer actions, expression mechanism coöperatively associated with the hammers for moving them toward and from the piano strings, and means operatively connected with said expression mechanism for taking up the slack in said flexible connections between the hammer actions and actuators. 110

12. In combination with the hammer actions of a piano, a plurality of actuators for said hammer actions, flexible connections between the actuators and hammer actions, a hammer rest rail, means for operating the hammer rest rail to move the hammers toward and from their strings, and means coöperatively associated with the means for operating the hammer rest rail to take up the slack in the flexible connections between the hammer actions and actuators. 120

13. In combination with the hammer actions of a piano, a plurality of actuators 130

therefor, flexible connections between said actuators and hammer actions, a hammer rest rail, means for flexing said rail and means operable simultaneously with the hammer rest-rail flexing means for taking up the slack in the said flexible connections.

14. In combination with the hammer actions of a piano, actuators therefor, flexible connections between said actuators and hammer actions, a hammer rest rail, means under the control of the performer for moving said rest rail to shift the position of rest of the hammers and mechanism coöperatively associated with the said manually operable means for taking up the slack in the said flexible connections between the actuators and hammer actions.

15. In combination with the sound-producing devices of a musical instrument, actuators therefor, flexible connections between said devices and actuators, expression mechanism coöperatively associated with the sound producing devices and means influenced by the operation of the expression mechanism for taking up the slack in the said flexible connections between the said devices and actuators.

16. In combination with the hammer actions of a piano, a plurality of actuators therefor, flexible connections between said actuators and hammer actions, and a manually operable slack adjusting rail coöperatively associated with said flexible connections.

35 17. In combination with the hammer actions of a piano, a plurality of actuators therefor, flexible connections between said actions and actuators, and a flexible rail for taking up slack in the said flexible connections between the hammer actions and actuators.

18. In combination with the hammer actions of a piano, a plurality of actuators therefor, flexible connections between said actuators and hammer actions, a slack adjusting rail over which said flexible connections pass, and manually operable means for shifting the position of said rail to take up the slack in the said flexible connections. 45

19. In combination with the hammer actions of a piano, actuating mechanism therefor, comprising a rotary shaft, and a plurality of friction shoes coöperatively associated therewith, a flexible connection between each shoe and a part of each hammer action, and means for taking up the slack in said flexible connections. 55

20. In combination with the hammer actions of a piano, actuating mechanism therefor, comprising a rotary shaft and a plurality of friction shoes coöperatively associated therewith, a flexible connection between each shoe and its appropriate hammer action, and a sectional slack-adjusting rail over which said flexing connections pass. 60

21. In combination with the hammer actions of a piano, actuating mechanism therefor, comprising a rotary shaft and a plurality of friction shoes coöperatively associated therewith, a flexible connection between each shoe and its appropriate hammer action, a sectional slack adjusting rail over which said flexible connections pass, and manually operable means for moving said rail. 65

In testimony whereof I have hereunto set 75 my hand in presence of two subscribing witnesses.

IRVING B. SMITH.
